UNITED STATES PATENT OFFICE.

GEORGE H. FORSYTH, OF CHICAGO, ILLINOIS, ASSIGNOR TO MOTOR WHEEL CORPORATION, OF LANSING, MICHIGAN, A CORPORATION OF MICHIGAN.

DISK WHEEL.

Application filed October 10, 1921. Serial No. 506,625.

To all whom it may concern:

Be it known that I, GEORGE H. FORSYTH, a citizen of the United States, residing at Chicago, in the county of Cook and State 5 of Illinois, have invented certain new and useful Improvements in Disk Wheels, of which the following is a specification.

In the case of disk wheels constructed of sheet metal it has been experienced that the 10 disk at times acts as a sounding board to amplify and disseminate any sounds emanating from the axle, the bearings, brakes, loose parts adjacent thereto or even from contact with hard objects in the road. The 15 dished shape of the disk and its confinement within the rim and about the hub impart thereto some of the resonant characteristics of a bell.

In the assembly of wheels of the steel 20 disk type it is recognized as important that the disk shall be rearwardly supported in that portion adjacent the hub as a means of reinforcing the sheet metal against bending in its vulnerable area. This has been done 25 in various ways but frequently the rear disk support has not minimized but often has increased the vibratory resonant qualities of the disk.

The primary object of the present invention 30 is the reduction of the disk vibration to the end that there shall be no sound emitted due to resonance and I accomplish this object preferably by utilizing the rear disk support as a means to mute the disk in a 35 manner analogous to the silencing of a bell by touching the same with the finger or other non-vibratory object.

The advantages of the present invention 40 may be realized in a measure by employing a non-metallic support; but where the support is of metal a facing of non-metallic character is preferably interposed in order to more efficiently mute the disk and also to prevent the wear which would otherwise result between contacting metal surfaces.

Whether the support be of wood or metal, 45 it is found advisable to so shape the supporting plate, either by bending to cup shape or routing out its central area, that 50 the support shall contact with the disk at a distance from the hub rather than throughout, in which case the interposed facing material, when used, may be confined to the annular contact area. The maintenance of 55 pressure contact either direct or indirect,

between the margin of the supporting plate and the disk is assured by the centrally relieved contour of the supporting plate whereby the margin of the plate is the more firmly pressed against the disk, as the central part is forced inwardly by the tightening of the securing bolts.

Furthermore, the employment of a yielding facing material such as a gasket or sheet of impregnated fibrous material serves incidentally to seal the joint between the disk and supporting plate, preventing the entrance of moisture and consequent rusting, a feature of construction which is not, in itself, novel.

In order that the invention may be readily understood in its application to disk wheels generally, I have in the accompanying drawing illustrated its application in different ways to one type of wheel, the same serving as a basis for detailed description of the invention. Obviously the details of construction would vary as applied to other types of disk wheels without departure from the essence of the invention, 80 wherefore it will be understood that the drawings and description are to be taken in an illustrative and not in an unnecessarily limiting sense.

In the drawing, 85 Fig. 1 is a central section through a single disk wheel having a wood filler plug forming a rear support and a mute for the disk; and

Fig. 2 is a similar view wherein a metallic rear support and disk is employed.

Having reference to the drawing the disk body is represented at 11 confined in its peripheral portion by the usual rim 12 and with its central or hub portion confined between the hub plates 13 and 14, the hub generally being indicated at 15. The central portion of the disk is clamped between the hub plates 13 and 14 upon a filler block, in this instance of wood comprising laminations 16 and 16^a angularly disposed, whereby the disk is rearwardly supported adjacent the hub against bending stresses. The marginal portion of the filler block, if of sufficiently non-vibratory character may bear directly upon the disk, or preferably the same is faced by a sound deadening substance as represented at 17, such as felt, canvas, asbestos, lead or any suitable muting composition. The facing material may, if 110

desired, be impregnated with a water-repellent substance such as asphaltic compositions.

The insert 17 may obviously extend 5 throughout a greater or less portion of the area of bearing contact between the support 16 and the disk 11.

Preferably the central or medial area 10 of the support is relieved, as at 16^b, so that the marginal contact at 17, whether direct 15 or indirect, between the support and disk, shall be firmly maintained at all times.

Referring to Fig. 2 of the drawing, the 15 rear disk-support is shown as comprising a cupped or arched plate 18 associated with the hub and advantageously though not necessarily with a filler ring 19, the central portion of the disk 11 and of the plate 18 being clamped upon the filler member 19 by means 20 of the hub plates 13 and 14. As herein illustrated by way of exemplification the marginal portion of the plate 18 is faced by an annulus 19 of muting material through which the supporting plate bears upon the 25 rear face of the disk.

Additionally, the transmission of sounds to the wheel may be minimized by the insertion of a sheet or strip of sound deadening material 20 between the rear hub plate 14 30 and the supporting plate 18 and between the front hub plate 13 and the disk 11, this being particularly advantageous in connection with the rear wheels of a vehicle where the function of the rear hub plate is performed by the brake drum containing elements which are not always noiseless in their 35 operation.

I claim:

1. In a disk wheel, the combination with 40 the hub and the disk body, of muting means

acting upon the disk whereby to reduce the resonance of the same, said muting means comprising a non-vibratory member associated with the hub and having contact with the rear face of the disk. 45

2. In a disk wheel, the combination with the hub and the disk body, of muting means 50 acting upon the disk whereby to reduce the resonance of the same, said muting means comprising a member associated with the hub and having contact with the rear face of the disk, the disk-contacting portion of the member faced with a sound deadening substance. 55

3. In a disk wheel, the combination with the hub and the disk body, of muting means 60 acting upon the disk whereby to reduce the resonance of the same, said muting means comprising a metal plate associated with the hub and having a marginal contact with the rear face of the disk, the disk-contacting portion of the plate faced with a sound deadening substance. 65

4. In a disk wheel, the combination with the hub and the disk body, of muting means 70 acting upon the disk whereby to reduce the resonance of the same, said muting means comprising a rearwardly arched plate associated with the hub and having marginal contact with the rear face of the disk in its medial portion, the disk-contacting portion of the plate faced with a sound deadening substance. 75

5. In a disk wheel, the combination with the hub and disk body, of a rear support for the disk, the bearing portion of the support faced with a sound deadening substance. 80

In testimony whereof I have hereunto subscribed my name.

GEORGE H. FORSYTH.
